ELECTRIC HEAT CONTROL MEANS FOR
REFRIGERATORSWestley G. Dahl, Montrose, Calif., assignor to
Thomas H. Harrison, Burbank, Calif.

Application November 6, 1936, Serial No. 109,462

14 Claims. (Cl. 62—5)

My invention relates to means for controlling the heat for gas refrigerators.

One of the principal objects of this invention is to provide an electric heating means for gas refrigerators, thereby greatly reducing fire hazards, and the inconvenience of obtaining fuel gas and the provision of elaborate fuel gas control means, and to provide a means in combination therewith for reliably controlling such heat.

Another important object of this invention is the provision of such control means which is controlled by and dependent upon the gas pressure within cooling portion, such as, the condenser and absorber, of the refrigerating system.

A further object of this invention is the provision of an electrically operated control means.

Another object of this invention is the provision of a simply and economically constructed mechanism for effecting these functions, and one which will not readily deteriorate or get out of order.

With these and other objects in view, as will appear hereinafter, I have devised such a control means having certain novel features of construction combination, and arrangement of parts and portions, as will be hereinafter described in detail and particularly set forth in the appended claims, reference being had to the accompanying drawing and to the characters of reference thereon, which form a part of this application, in which:

The figure of the drawing is a diagrammatic view of a gas refrigerator system showing my electric heat control means embodied therein, the gas refrigerator system, consisting of prior art structure, being shown diagrammatically, and the parts and features illustrating my present invention being shown in section.

The refrigerating apparatus or mechanism is similar to the "Electrolux" refrigerator now in common use. As far as the present invention is concerned it consists essentially of a gas generator A, a box cooling evaporator coil B, a gas heat exchanger C, a condenser D, and an absorber E which contains refrigerating fluid under pressure.

In the embodiment of my invention, as illustrated in the drawing, I have provided a pressure tank 1 which is connected, by a pipe 2, to the absorber E, and, by a pipe 3, to the condenser D.

The tank or reservoir has a pressure yieldable diaphragm 4 at one end, the distortion of which controls and regulates the refrigerator by controlling the heating means 11 of the generator A. This heating means is an electric element, which

is heated by a source of electric energy, which in this instance is a storage battery 12. One wire 13 directly connects the element to the battery. The other wire 14 is connected to multiple contact rheostat 15 having a pivoted controller 16. 5

Against the diaphragm, and preferably in axial alignment with the tank 1 is a plunger 21 which is resiliently forced against the diaphragm by a manually adjustable pressure regulator or temperature control. Between the latter control and the plunger is a compression spring 23.

A control lever 31 is pivotally mounted at one end 31^a and is adapted to be oscillated near its pivot by knife edges 21^a of the plunger. The free end of the lever is pivotally connected with the controller. This lever also may be connected by a wire 32 to the battery.

As the diaphragm is forced outwardly, the lever 31 is rocked and the controller 16 rotated to engage contacts of the rheostat and thereby add 20 resistance between the source electrical energy and the heating element 11. Full rotation of the controller 16 breaks the circuit to the heating element, which condition continues until the diaphragm 4 is drawn inwardly. 25

Though I have shown and described a particular construction, I do not wish to be limited to the same, but desire to include in the scope of my invention the construction, combination, and arrangement as set forth in the appended claims. 30

I claim:

1. In a heat control means for refrigerators, a generator, means for heating the same, cooling means connected with the generator, a gas pressure reservoir connected with the cooling means, 35 a diaphragm forming part of the reservoir, means for controlling the heating means, and a manual adjusting means operatively connecting the diaphragm with the controlling means for readily and quickly varying the responsiveness of the 40 heat control means.

2. In a heat control means for refrigerators, a generator, means for heating the same, cooling means connected with the generator, a gas pressure reservoir connected with the cooling means, 45 a diaphragm forming part of the reservoir, means for controlling the heating means, a plunger in operative engagement with the diaphragm, and a lever means operatively connecting the plunger with the control means.

3. In a heat control means for refrigerators, a generator, means for heating the same, cooling means connected with the generator, a gas pressure reservoir connected with the cooling means, 50 a diaphragm forming part of the reservoir, means

50

55

- for controlling the heating means, a plunger in operative engagement with the diaphragm, and a lever pivoted at one end and shiftable intermediate its ends by the plunger, the free end of the lever being connected to the control means. 5

4. In a heat control means for refrigerators, a generator, means for heating the same, cooling means connected with the generator, a gas pressure reservoir connected with the cooling means, 10 a diaphragm forming part of the reservoir, means for controlling the heating means, an adjustable plunger resiliently held in operative engagement with the diaphragm, and a lever means operatively connecting the plunger with the control means.

15 5. In a heat control means for refrigerators, a generator, means for heating the same, cooling means connected with the generator, a gas pressure reservoir connected with the cooling means, a diaphragm forming part of the reservoir, means 20 for controlling the heating means, an adjustable plunger resiliently held in operative engagement with the diaphragm, and a lever pivoted at one end and shiftable intermediate its ends by the plunger, the free end of the lever being connected to the control means.

25 6. In a heat control means for refrigerators, a generator, an electric means for heating the same, cooling means connected with the generator, a gas pressure reservoir connected with the 30 cooling means, a diaphragm forming part of the reservoir, a rheostat for the electric heating means, and a manually adjusting means operatively connecting the diaphragm with the rheostat.

35 7. In a heat control means for refrigerators, a generator, an electric means for heating the same, cooling means connected with the generator, a gas pressure reservoir connected to the cooling means, a diaphragm forming part of the reservoir, a rheostat for controlling the heating means, 40 a plunger in operative engagement with the diaphragm, and a lever means operatively connecting the plunger with the rheostat.

45 8. In a heat control means for refrigerators, a generator, an electric means for heating the same, cooling means connected with the generator, a gas pressure reservoir connected to the cooling means, a diaphragm forming part of the reservoir, a rheostat for controlling the heating means, 50 a plunger in operative engagement with the diaphragm, and a lever pivoted at one end and shiftable intermediate its ends by the plunger, the free end of the lever being connected to the rheostat.

55 9. In a heat control means for refrigerators, a generator, an electric means for heating the same, cooling means connected with the generator, a 55

gas pressure reservoir connected to the cooling means, a diaphragm forming part of the reservoir, a rheostat for controlling the heating means, an adjustable plunger resiliently held in operative engagement with the diaphragm, and a lever means operatively connecting the plunger with the rheostat. 5

10. In a heat control means for refrigerators, a generator, an electric means for heating the same, cooling means connected with the generator, a 10 gas pressure reservoir connected to the cooling means, a diaphragm forming part of the reservoir, a rheostat for controlling the heating means, and a lever pivoted at one end and shiftable intermediate its ends by the diaphragm, the free 15 end of the lever being connected to the rheostat.

11. In a heat control means for refrigerators, a generator, an electric means for heating the same, cooling means connected with the generator, a 20 gas pressure reservoir connected with the cooling means, a diaphragm forming part of the reservoir, a pivoted lever shiftable about its pivot by the diaphragm, and a rheostat connected to the heating means for controlling the electric energy thereto, said rheostat having an arm operatively 25 connected to the lever.

12. In a heat control means for refrigerators, a generator, an electric means for heating the same, cooling means connected with the generator, a gas reservoir connected with the cooling means, 30 operating means in connection with the generator and responsive to the physical conditions of the gas in the cooling means, and a rheostat for the electric heating means, said rheostat being operatively connected with said operating means. 35

13. In a heat control means for refrigerators, a generator, an electric means for heating the same, cooling means connected with the generator, a gas reservoir connected with the cooling means, operating means in connection with the generator and responsive to the physical conditions of the gas in the cooling means, a rheostat for the electric heating means, and a manual adjusting means connecting the operating means with the rheostat. 40

14. In a heat control means for refrigerators, a generator, an electric means for heating the same, cooling means connected with the generator, a gas reservoir connected with the cooling means, operating means in connection with the generator and responsive to the physical conditions of the gas in the cooling means, and a rheostat connected to the heating means for controlling the electric energy thereto, said rheostat having an arm operatively connected to said operating means. 45
